Jas. H. Churchill
ATTORNEY.

UNITED STATES PATENT OFFICE.

ALBERT L. HOWARD, OF BRAINTREE, MASSACHUSETTS, ASSIGNOR TO ASHTON HAMILTON, OF BROCKTON, MASSACHUSETTS.

BOW NECKTIE.

Application filed June 11, 1925 Serial No. 36,526.

This invention relates to a necktie of that character commonly known as a bow-tie, and has for its object to provide a necktie of the character described, which is superior 5 in many respects to those now commonly made, which is less expensive and more durable, as will be described.

To this end the bow-tie is made of leather and comprises an endless longitudinal member 10 having opposing halves in close proximity to each other and substantially parallel, and a transverse endless member of smaller diameter than the width of the longitudinal member and encircling the latter near its 15 center to reduce the width of the longitudinal member near its center and form end wings of greater width than said reduced center portion.

The particular features of the invention 20 will be pointed out in the claim at the end of this specification.

Fig. 1 is a front elevation of a leather bow-tie embodying this invention.

Fig. 2, a rear view of the bow-tie shown 25 in Fig. 1.

Fig. 3 represents a ring of leather from which the longitudinal member is formed.

Fig. 4 represents the ring shown in Fig. 3 as collapsed to form the longitudinal member.

30 Fig. 5, represents the endless transverse member shown in Fig. 1.

Fig. 6, is a front elevation of a bow-tie of a different shape from that shown in Fig. 1, and

35 Fig. 7, a rear view of a bow-tie like that shown in Fig. 1, with a modified fastening device.

Referring to the drawing and especially Figs. 1 to 5 *a* represents a bow-tie having 40 a substantially small central portion 10 and relatively wide wings 12. The bow-tie *a* may be made from leather or imitations of leather, and will be hereinafter referred to as a leather bow-tie.

45 The bow-tie *a* is composed of two endless members *b*, *c* of leather, which may be designated the longitudinal and transverse members respectively.

The longitudinal member *b* is made by taking 50 a strip of leather of the desired or proper length, overlapping its free ends and securing them together by stitches 14 or otherwise so as to form a ring 15 of leather of relatively large diameter (see Fig. 3).

The leather ring 15 is then folded together 55 or collapsed along its diameter so as to form the longitudinal member shown in Fig. 4, which is provided with two substantially parallel opposing halves or members 17, 18, with the stitches 14 located at the center of 60 one of said halves.

The transverse endless member *c* is made from a smaller strip of leather by stitching or otherwise securing its ends together, to form a leather ring (see Fig. 5), which is 65 relatively smaller than the ring from which the longitudinal member is formed.

The ring or endless member *c* is then slipped over the longitudinal member *b*, 70 which may be effected by folding the longitudinal member lengthwise, and the endless member *c* is positioned substantially at the center of the longitudinal member, with the stitched ends of the strip from which the member *c* is formed located at the rear 75 side of the longitudinal member.

After the transverse ring *c* has been properly positioned on the longitudinal member *b*, the end of the latter member which was 80 folded longitudinally to permit the member *c* to be slipped over the same, is then unfolded and spread out to form one of the wings.

The relatively small transverse ring member *c* compresses the longitudinal member at the center and is frictionally held in its adjusted position without the necessity of employing stitches or other fastening means.

The leather strips from which the endless members *b*, *c* of the bow-tie are formed may 85 have their outer surfaces provided with any form of design *d* desired, which may be obtained by embossing, printing or coloring, or by perforations.

The leather strips employed will preferably be provided with a grain or pebbled surface on which the design is formed and very attractive and pleasing color effects may be obtained by providing the grain or pebbled surface with a design thereon.

The design *d* may cover substantially the 90 whole of the outer surface of the members *b*, *c*, as represented in Fig. 1, or it may cover only a portion of said surface as represented in Fig. 6.

The bow-tie may be provided with the 95 usual means for attaching it to the collar button of the wearer, and in Fig. 1, one form of attaching means is shown, which consists of

an elastic member 30, provided at one end with an eye 31, which is slipped through the transverse member *c* at the rear side of the tie (see Fig. 2), and made of sufficient length 5 to pass around the neck of the wearer.

Another form of attaching means is shown in Fig. 7, which consists of a relatively stiff member 33 designed to have its ends inserted between the folds of the collar, not shown, 10 and provided with a wire member 34 for engagement with the collar button, and which also may be used to attach the member 33 to the transverse member *c*.

It will be observed by reference to Figs. 13 1 and 6 that the members *b*; *c*, may be provided with the same design represented in Fig. 1, or with a different design as represented in Fig. 6, and in this way a large variation in appearance may be obtained.

From the above description, it will be observed that the bow-ties herein described, 25 may be made at a minimum expense, as the process of manufacture is simple and the leather is of sufficient stiffness to retain its shape, without the use of card-board or like stiffening members now commonly employed with bow-ties made from pieces of silk or cotton fabric.

Furthermore the members *b*, *c* being of 30 leather are practically indestructible, in that they can be worn by persons having a beard without becoming worn by contact with the beard.

So also the leather members do not fray,

and are washable without distortion of their 25 shape.

The ring-like or endless construction of the members *b*, *c* enables the bow-tie to be quickly and easily taken apart, washed and again assembled by users who are inexperienced in the use of needle and thread, as it is only necessary to slip the transverse ring member *c* off one end of the longitudinal member *b*, wash both members, and reassemble them. 40

What I claim is:

A bow-tie comprising a longitudinal member formed of a single piece of thin flexible leather having its ends overlapped and secured together in proximity to the said ends and shaped to provide the longitudinal member with substantially parallel opposing halves, one of said halves being composed of a single thickness or layer for its entire length, and the other half being composed of a single thickness or layer for its entire 55 length except at the overlapping ends forming part thereof, and a transverse annular member formed of a single piece of leather 60 slidable on said longitudinal member and of a diameter materially less than the width of the halves of said longitudinal member to compress the latter near its center and to be frictionally held thereon and provide the longitudinal member with wings on opposite sides of the transverse member. 65

In testimony whereof, I have signed my name to this specification.

ALBERT L. HOWARD
